US00D997979S

(12) **United States Design Patent** (10) **Patent No.:** **US D997,979 S**
Coenen et al. (45) **Date of Patent:** **** Sep. 5, 2023**

(54) **DISPLAY PANEL PORTION WITH A COMPUTER ICON**(71) Applicant: **Reveal Energy Services, Inc.**, Houston, TX (US)(72) Inventors: **Erica Wilhelmina Catharina Coenen**, Spring, TX (US); **Siarhei Miseiko**, Minsk (BY); **Scott Seften**, Sugar Land, TX (US); **Sean Andrew Spicer**, Houston, TX (US)(73) Assignee: **Reveal Energy Services, Inc.**, Houston, TX (US)(**) Term: **15 Years**(21) Appl. No.: **29/863,440**(22) Filed: **Dec. 19, 2022****Related U.S. Application Data**

(62) Division of application No. 29/738,794, filed on Jun. 19, 2020, now Pat. No. Des. 976,938.

(51) **LOC (14) Cl.** ..... **14-04**(52) **U.S. Cl.**USPC ..... **D14/486**(58) **Field of Classification Search**USPC **D14/485-495**

Primary Examiner — Katherine A Holbrow*Assistant Examiner* — Christopher M Spivey(74) *Attorney, Agent, or Firm* — Fish & Richardson P.C.(57) **CLAIM**

The ornamental design for a display panel portion with a computer icon, substantially as shown and described.

DESCRIPTION

The FIGURE is a front view of the display panel portion with a computer icon, showing our new design.

The broken lines showing a portion of a display panel are included for the purpose of illustrating portions of the article and form no part of the claimed design. All other broken lines in the drawings are for the purpose of illustrating portions of the computer icon that form no part of the claimed design.
